PUMP OR THE LIKE

Albert O. Price, Leesville, Ohio, assignor of one-half to Vincent Palumbo, Cleveland Heights, Ohio

Application April 27, 1946, Serial No. 665,472

10 Claims. (Cl. 103—103)

1

This invention relates to fluid impellers, pumps, or the like, especially to fluid pumps having a combined centrifugal and suction action.

A general object of this invention is to provide a durable, efficient pump using both a centrifugal and a suction pumping action.

Another object of the invention is to provide a sturdy construction having a minimum of functional parts.

A further object of the invention is to provide a stationary distributor head, desirably star-shaped, that is straddled by the rotor blades.

Another object of the invention is to deliver the incoming fluid as near as possible to the zone of the blades' action and to distribute it throughout the circumference thereof.

Still another object of the invention is to provide a distributor head having peripheral suction pockets through the "trailing" surfaces of which, relative to the direction of blade movement, the fluid inlet ports open.

Another object of the invention is to provide an inexpensive, easily assembled construction.

The foregoing, and other objects of the invention which will become apparent as the specification proceeds, are realized by the provision of apparatus shown in the accompanying drawings, wherein:

Fig. 1 is a vertical section taken through a pump embodying the invention;

Fig. 2 is a section taken on line 2—2 of Fig. 1;

Fig. 3 is an elevation of the rotor used in the pump;

Fig. 4 is a section on line 4—4 of Fig. 3;

Fig. 5 is a side elevation of the distributor head, and

Fig. 6 is a front elevation thereof.

In general, the disclosed structure, which is to be taken as illustrative rather than as limiting, includes a distributor head having at least a peak and a valley formed on its periphery, constituting what has been referred to as a suction pocket; an inlet means connecting the inlet to the distributor head which has at least one port opening through the so-called "trailing" surface of a suction pocket, and rotor blades mounted to travel in rapid succession in close proximity to and past the pocket so that the blades not only drive fluid through the pump by their forward faces but also draw fluid out of the pocket by suction created by the rear faces of the blades.

Referring more specifically to the accompanying drawings, there is shown a pump 10 which includes an open sided casing 11 that is completed to form a chamber 12 by a casing plate 13

5 which is removably secured to the casing 11. Note that the casing 11 has diametrically opposed outlets 14 and that the interior surface of the peripheral wall of the chamber 12 is eccentric or spiral between said parts. The casing 11 may have foot brackets 15 formed integrally therewith for mounting the structure.

An important feature of the invention resides in the provision of a substantially star-shaped, disc-like distributor head 16 which is stationarily positioned in the chamber 12 and has a tubular boss 17 extending from one side thereof. The distributor head 16, according to the invention, must have a number of suction pockets, shown as 18 defined by peaks formed on its periphery and preferably the head is symmetrically formed, but it need not have peripheral suction pockets or notches, of the exact shape shown, in all cases. Fluid conduits, or ports 18 are formed in the distributor head 16 and extend substantially tangentially from the bore of the boss 17, or considering the head as a whole, in a slightly rearwardly inclined, radial direction with relation to the direction of rotation of the pump's rotor, as 20 pointed out hereinafter.

The ports 18 all open through corresponding sides of the points on the head with one edge of each of the ports extending substantially to the tip of the point. The boss 17 has a shoulder 19 25 on its periphery that seats on the casing plate 13, while a nut 21 engages with a thread on the boss 17 for retaining the distributor head 16 and the casing plate 13 in fixed relation. If necessary, suitable packing (not shown) may be positioned between the casing plate 13 and boss 17, or between plate, boss and lock nut. An inlet pipe 22 is communicatively connected to the boss 17 by a standard L fitting 23.

As shown in Fig. 1, the distributor head 16 is 30 centrally positioned in the chamber, and a rotor 24, consisting of a plurality of segmental sections—desirably two—is assembled around the head 16 with each section having substantially U-shaped blades 25 that straddle the distributor head 16. The blades 25 are formed from sheet material and include side portions 26 and transverse end portions 27, the side portions 26 being anchored, in any known manner, as by brazing, in slots formed in the edges of sectional hubs 28 35 and 29. These hubs 28 and 29 are ring-like in shape and are journaled on cylindrical surfaces of the distributor head 16. It will be noted that the side portions 26 of the blades 25 extend radially inwardly on both sides of the distributor head 16 to the depth of the peripheral suction pockets

of the distributor head. The direction of rotation of the rotor 24 is indicated by the arrow A in Fig. 2, and as seen in that view the side and end portions 26 and 27 are rearwardly inclined from the edge portions thereof that are immediately adjacent the distributor head. While said portions 26 and 27 are shown as straight from edge to edge, they may be curved, if desired, and their angle and direction of inclination may vary, or they may lie in radial planes. The present preferred direction of inclination, however, is as illustrated. Since the blades 25 fit closely around the distributor head and have minimum clearance in the chamber 12, each time a blade passes one of the peripheral pockets of the head, a suction is created therein that draws fluid through the ports 18. By the centrifugal action of the blades, the fluid is hurled outwardly and about the spiral portions of the chamber 12 to the outlet ports 14.

The portions of maximum thickness of the peripheral wall of the casing adjacent the outlet ports, are given a formation, as indicated at 31, that directs fluid into the outlet ports with a minimum of fluid turbulence. Flow of fluid through the pump is also facilitated greatly by the fact that the aggregate cross sectional area of the ports 18 approximates that of the central inlet passage of the pump. Also, by the arrangement of said ports 18, the liquid is conveyed to the very zone of the blade action and is distributed throughout the circumference thereof.

As best shown in Figs. 3 and 4, each hub 28 and 29 is split diametrically, and a lock nut 32 is engaged with a threaded area on the sections of the hub 28 (Fig. 1) to secure said sections together. A set screw 33 may be provided to retain the nut 32 fixed on the hub 28. The hub 29 is journaled on a solid boss 34 formed on the distributor head 16 on the side thereof opposite the tubular boss 17 and the sections of the hub 29 are secured, by screws 35, to an annular flange 40 formed on the end of a drive shaft 36. The flange 40 is reamed out so that the heads of the screws 35 are flush with its outer surface. The drive shaft is shown as tubular on its inner end, to reduce its weight, and as having a solid portion that extends beyond the casing 11. A suitable driving member 37, shown as a pulley, is keyed to sleeve 38 which, in turn, is keyed to the drive shaft 36. By this means, the pump may be motor driven by a belt, not shown.

The casing 11 is sealed in any conventional manner and it is shown as fitted with a flanged bearing 39 received in a hollow boss 41 formed integrally with the casing 11, the flange of said bearing 39 seating on a shoulder 42 formed at the inner end of the boss. A nut 43 threadedly engages the bearing 39 by means of which the bearing flange is drawn up against the shoulder 42 to secure the bearing to the housing. A conventional packing gland 44 is incorporated in the bearing 39 to seal the joint between it and the shaft 36 when a gland nut 45 is drawn up within the threaded recess of the bearing.

Figs. 3 and 4 bring out the sturdy construction of the rotor 24 and the multiple, closely spaced blades 25 thereof which blades, in cooperation with the design of distributor head 16, shown in detail in Figs. 5 and 6, contribute largely to the efficiency of the pump. A very important feature of the invention is the arrangement of the inlet ports by which the incoming fluid is delivered in close proximity to the orbit of the

blades and is distributed throughout the entire circumference thereof.

From the foregoing description, it is seen that an inexpensive, durable, efficient pump is provided through which the objects of the invention are realized.

While in accordance with the patent statutes, one embodiment of the invention has been specifically illustrated and described, it should be clearly understood that the scope of the invention is not limited thereto, or thereby, but is defined in the appended claims. For example, any structure affording the feature of port and blade arrangement and cooperation above described, falls within the purview of the invention.

Having thus described my invention, what I claim is:

1. A pump or the like comprising a casing having a substantially annular chamber therein and having an outlet formed in its periphery, a disc-like distributor head stationarily positioned centrally within said casing and having peripheral suction pockets, said distributor head having a chamber formed therein for receipt of fluid input and having ports leading from the chamber

20 to said pockets, and a rotor journaled on said distributor head, said rotor carrying a plurality of substantially U-shaped blades that straddle said distributor head in immediate relationship to the periphery thereof.

2. A pump or the like as defined by claim 1, wherein said blades are inclined rearwardly and outwardly relative to the direction of rotation of the rotor.

3. A pump comprising a casing having a substantially annular chamber therein and having diametrically opposed outlets formed in its periphery, said casing being slightly eccentric to increase the chamber size gradually adjacent

40 the forward side of each of said outlets, a substantially star-shaped disc-like distributor head stationarily positioned within said casing, said distributor head having a tubular boss extending from one side thereof with the bore thereof

45 connecting to substantially radially positioned ports leading therefrom to the trailing sides of the points of the head immediately adjacent the periphery thereof, a rotor journaled on said distributor head, means for driving said rotor, and a plurality of substantially U-shaped blades incorporated in said rotor and adapted to straddle said distributor head in immediate relationship to the sides and points of said distributor head.

4. A pump or the like as defined by claim 3, 55 wherein the side and end portions of said U-shaped blades are inclined rearwardly and outwardly relative to the direction of travel of the blades.

5. A pump or the like comprising a casing having a substantially annular chamber therein, outlet means associated with the periphery of said casing, a substantially star-shaped distributor head stationarily positioned centrally within said casing, said distributor head having an annular chamber formed therein for receipt of fluid input and having ports leading from the chamber to the periphery of the head immediately adjacent the points thereof, and a rotor journaled on said distributor head, said rotor

65 carrying a plurality of substantially U-shaped blades that straddle said distributor head in immediate relationship to the sides and points of said distributor head and in close relationship to the sides of the casing.

75 6. A pump or the like comprising a casing hav-

ing a substantially annular chamber therein and having outlets formed in its periphery, a substantially star-shaped distributor head stationarily positioned substantially centrally within said casing, said distributor head having a tubular boss extending from one side thereof, said distributor head also having ports formed therein from the bore of the boss to the trailing sides of the points of said head immediately adjacent the periphery thereof, inlet means connected to the tubular boss of said distributor head, a rotor journaled on said distributor head, means for driving said rotor, and a plurality of substantially U-shaped blades incorporated in said rotor that straddle said distributor head in immediate relationship to the sides and points of said head.

7. In a pump, a distributor head characterized by peripheral suction pockets, said pockets being defined by circumferentially spaced peaks, the head having an inlet and ports leading therefrom to the trailing edges of said peaks, and substantially U-shaped rotor blades mounted to straddle said distributor head for rotation in close proximity to and past said peaks, the side portions of said blades extending radially inwardly substantially the depth of said pockets.

8. In a pump, a symmetrical, disc-shaped, peaked distributor head; said distributor head having inlet ports formed therein leading to the trailing edges of its peaks; and substantially U-shaped blades mounted to straddle said distributor head for rotation in close proximity to and past the peaks of said distributor, said blades having planar side and end faces that are rearwardly inclined from the edges thereof immediately adjacent said distributor head.

9. A structure comprising a casing having apertured end walls and enclosing a substantially annular chamber, and two relatively rotatable elements occupying said chamber, each provided with an axial extension that projects through the aperture of one of the end walls, one of said elements consisting of a body having circumferentially spaced peripheral pockets and fluid supply ducts opening therewith, and the other including substantially U-shaped blades straddling the peripheral portion of said body.

10. In combination, two relatively rotatable elements, one consisting of a body having circumferentially spaced peripheral pockets and fluid supply ducts opening therewith, and the other characterized by substantially U-shaped blades straddling the peripheral portion of said body, each element being provided with an axial extension substantially aligned with that of the other.
